DESIGN FOR A TOY

Frank Caplan and Remo Bufano, New York, N. Y.

Application September 18, 1944, Serial No. 115,342

Term of patent 7 years

(Cl. D34—2)

To all whom it may concern:

Be it known that we, Frank Caplan and Remo Bufano, citizens of the United States, residing at New York, in the county and State of New York, and whose post-office addresses are respectively, 62 Park Terrace West, New York, N. Y., and Waverly Place, New York, N. Y., have invented a new, original, and ornamental Design for a Toy, of which the following is a specification, reference being made to the accompanying drawing, forming a part thereof.

Fig. 1 is a side view of a toy showing our new design;

Fig. 2 is a rear-end view thereof; and

Fig. 3 is a perspective view thereof on a reduced scale with parts in a different position.

We claim:

The ornamental design for a toy, substantially as shown.

FRANK CAPLAN.
REMO BUFANO.
